(57) **CLAIM**

The ornamental design for multipurpose stemware holder tray, as shown and described.

DESCRIPTION

FIG. 1 is a perspective view of a multipurpose stemware holder tray, showing our design;

FIG. 2 is top view thereof;

FIG. 3 is a bottom view thereof;

FIG. 4 is a side view thereof;

FIG. 5 is an opposing side view thereof;

FIG. 6 is an end view thereof;

FIG. 7 is an opposing end view thereof;

FIG. 8 is a perspective view of a second embodiment thereof;

FIG. 9 is a top view thereof;

FIG. 10 is a bottom view thereof;

FIG. 11 is a side view thereof;

FIG. 12 is an opposing side view thereof;

FIG. 13 is an end view thereof; and,

FIG. 14 is an opposing end view thereof.

1 Claim, 10 Drawing Sheets
